2 SHEETS—SHEET 2.

UNITED STATES PATENT OFFICE.

FREDERICK F. BALLARD, OF DAVENPORT, IOWA.

OPERATING-HEADLIGHT.

1,252,989.

Specification of Letters Patent.

Patented Jan. 8, 1918.

Application filed March 1, 1917. Serial No. 151,788.

To all whom it may concern:

Be it known that I, FREDERICK F. BALLARD, a citizen of the United States, residing at Davenport, in the county of Scott and State of Iowa, have invented certain new and useful Improvements in Operating-Headlights; and I do declare the following to be a full, clear, and exact description of the invention, such as will enable others skilled in the art to which it appertains to make and use the same.

My invention relates to improvements in headlights for use by surgeons, dentists and opticians and is designed to provide an adjustable electric lamp to deliver rays upon the object to be inspected or operated upon.

An object of my invention is to provide an electric headlight which will be operated by current supplied by dry cells carried on the body of the operator.

With this and numerous other objects in view my invention resides in the novel features of construction and in the combination and arrangement of parts as will be fully set forth in the specification and claims.

In the accompanying drawings:

Figure 1 is a perspective view of the headlight applied;

Fig. 2 is a side elevation of the headlight;

Fig. 3 is a horizontal section of the clamping jaws on the lamp;

Fig. 4 is a perspective view of the battery case and support therefor, and,

Fig. 5 is a detail perspective view of the battery case in closed position.

Reference is now had to the drawings in which I have shown a headband 1 comprising two spring metal bands 2 and 3 adjustably connected by a longitudinally projecting tongue 4 on one end of one of the bands and adapted for reception in a longitudinal slot 5 in the adjacent end of the other band 3 and held in adjusted position by a clamp 6. The extreme end of the rear section 2 of the headband is provided with lateral extensions 7 for engagement with the back of the head and the front section 3 is provided with extensions 8 adapted to bear

against the forehead of the operator to hold the head-piece in proper position. The extensions 7 and 8 have pads 9 on their inner faces to contact the head so as to more firmly hold the device in position. The headband is also provided with guides 9' in the form of eye screws threaded into sockets in said

band and projecting from its outer face for a purpose to be hereinafter set forth.

Secured to the front section 3 of the headband are upper and lower flat metal plates 10 and 11 bent substantially L-shaped and having their longer forwardly projecting arms secured together by rivets or the like and oppositely directed attaching feet 12 and 13 riveted or otherwise secured to said front section, said feet being seated in recesses in said section so that the outer faces of the feet and head section will be in the same plane.

The outer portions of the upper and lower L-shaped plates 10 and 11 are bent upwardly and downwardly respectively at acute angles as shown in Fig. 1 and then directed horizontally in parallel spaced relation to form clamping plates or jaws 14 and 15 which are held together by an adjusting bolt 20 which extends through vertically alined apertures in said clamping plates or jaws 14 and 15 near the juncture of the horizontal and angular portions. Adjacent the extreme ends of the clamping plates or jaws is another pair of vertically alined apertures whose purpose will be hereinafter set forth.

The casing 16 of an electric or other lamp is provided at its base with a pair of longitudinally extending parallel spaced clamping jaws 17 having laterally outwardly directed attaching feet secured to said base, said jaws having adjacent the base of the lamp a pair of transversely alined apertures through which extends a bolt to hold in position between said jaws, a spacing block 19 having an aperture therein for the reception of said bolt whereby the jaws will be rigidly held apart.

The clamping plates or jaws 17 are provided substantially midway their lengths with a second pair of transversely alined apertures to receive an adjusting bolt 20' whose purpose will be hereinafter described.

Adjacent the extreme ends of plates or jaws 17 is a pair of transversely alined apertures whose purpose will be hereinafter set forth.

The two pairs of clamping plates or jaws are connected by a link 21 on each end of which is a head or ball 22 to be clamped between the adjacent inner faces of the jaws and received in the apertures which form seats therefor and are positioned near the extreme ends of said jaws as hereinbefore stated.

The current used by the lamp is obtained from dry cells carried in a case 23 formed from any suitable flexible material. The case comprises an elongated pocket open at 5 each end and on one side and having flaps 24 at each end adapted to be folded inwardly over the outer ends of the cells which are wired together in the usual manner.

- 10 This case 23 has upper and lower longitudinal flaps 25 and 26 adapted to cover the cell and have their adjacent edges detachably fastened together by any suitable means, the whole case being adapted to be 15 positioned on the back of the operator and held in said position on a belt or suspenders 29 as shown.

For the purpose of conducting current from the cells to the lamp an electric lamp 20 cord 27 is provided and is connected to the cells and then extended through the guides 9' on the headband 1, and then through a guide 9'' which is mounted on the upper plate or jaw 14 of a clamp which projects 25 from the headband after which said cord is passed through an opening in the side of the casing 16 of the lamp. For the purpose of breaking the circuit a pair of plugs and sockets 28 are placed therein at a point 30 near the case 23.

In use the case containing the cells is attached to the body by means of the belt or suspenders and then the headband is adjusted to the size of the operator's head 35 after which it is positioned on the head with the extensions 7 contacting the back thereof and the extensions 8 contacting the forehead. The plugs and sockets are connected to close the circuit whereupon the 40 electric lamp may be used to deliver rays of light upon the object to be inspected or operated upon. From the connection between the headband and the lamp casing it is apparent that said lamp may be adjusted 45 to throw light rays in any desired direction.

From the foregoing description and operation of my improved operating head-light the manner of applying the same to 50 use and the operation thereof will be read-

ily understood and it will be seen that I have provided a simple and efficient means for carrying out the objects of the invention.

I claim:

1. In a device of the class described, a support, a pair of clamping plates or jaws on said support, a lamp having a pair of rearwardly extending clamping plates or jaws on its casing, a link between the pairs of jaws, said link having a ball on each end to be received and held in seats formed in the adjacent inner faces of each pair of clamping plates or jaws. 60

2. In a device of the class described, a headband, a pair of forwardly projecting clamping plates or jaws on said headband, a lamp, a pair of rearwardly extending clamping plates or jaws on the casing of said lamp, each pair of clamping plates or 70 jaws having alined apertures in their adjacent jaws to form seats, a link between the pairs of clamping plates or jaws, said link having a ball on each end to be received and held in said seats. 75

3. The combination of a headband, a lamp casing, a link having a ball at each end, a pair of resilient clamping jaws rigidly secured to the lamp casing at one end and having at their opposite ends circular 80 openings of a smaller size than the diameter of one of said balls to receive the same, means arranged between the ends of said arms for drawing their apertured ends into engagement with said ball, a pair of resilient plates secured together adjacent one end and having said ends fastened to said headband, the opposite ends of said plate being spaced apart and formed with circular openings of less diameter than the other 85 ball on said link, and means for drawing said spaced portions of the last mentioned plates together to clamp them on the ball. 90

In testimony whereof I have hereunto set my hand in the presence of two subscribing 95 witnesses.

FREDERICK F. BALLARD.
